J. HERZOG.
RESONATOR.

APPLICATION FILED FEB. 26, 1919.

Patented Nov. 22, 1921.

John Herzog INVENTOR
BY *H. C. Bl. Willcox* ATTORNEY

UNITED STATES PATENT OFFICE.

JOHN HERZOG, OF SAGINAW, MICHIGAN, ASSIGNOR TO SONORA PHONOGRAPH COMPANY, INC., OF NEW YORK, N. Y., A CORPORATION OF NEW YORK.

RESONATOR.

1,397,733.

Specification of Letters Patent.

Patented Nov. 22, 1921.

Application filed February 26, 1919. Serial No. 279,387.

To all whom it may concern:

Be it known that I, JOHN HERZOG, a citizen of the United States, residing at Saginaw, in the county of Saginaw and 5 State of Michigan, have invented certain new and useful Improvements in Resonators; and I do hereby declare the following to be a full, clear, and exact description of the invention, such as will enable others 10 skilled in the art to which it appertains to make and use the same.

This invention relates to resonators and pertains more particularly to an improved construction for horns of sound-reproducing 15 instruments such as phonographs and the like.

The objects of my improvement are, first, to provide a horn having a sound-carrying channel of angular cross-sectional shape, the 20 walls of the channel being in the form of warped or twisted planes, whereby the resonance of the horn is increased and the quality or timbre of the sound is unimpaired by its transmission through the resonator.

25 A further object is to provide a horn of such construction and shape that it can be made of wood at relatively small expense and yet be of such shape that that part of the tapered body near the smaller end of 30 the horn may be bent laterally and upwardly to a position such that the tone arm of a phonograph may be joined to the upper end of the horn at one corner of the motor board of the instrument, while enabling the horn 35 to deliver the sound from its flared end extending across the front of the cabinet of the phonograph. Thus the horn, in its preferred form, passes underneath the motor, and then laterally and upwardly to the corner 40 of the motor board, occupying small space and enabling the horn and the mechanism of the phonograph to be arranged compactly.

With the foregoing and certain other objects in view which will appear later in the specification, my invention consists in the devices described and claimed and the equivalents thereof.

In the drawings, Figure 1 is a perspective 50 view of a resonator or horn built in accordance with my invention and shown as it would appear when viewed from one side.

Fig. 2 is a rear end view shown inverted.

Fig. 3 is a top plan view of the form of horn shown in Fig. 1.

55

Fig. 4 is a perspective view of the horn as seen from above.

Fig. 5 is a side elevation.

Fig. 6 is a perspective view, showing the side opposite that illustrated in Fig. 1.

60

As is clearly shown in the drawings, the horn consists in a body 1 having an inlet 2 and an enlarged flaring sound outlet 3.

In cross-sectional shape the body of the horn is preferably angular. In the preferred form illustrated in the drawings it is shown of rectangular cross section, but it may be square or hexagonal, or of any other suitable angular form.

As illustrated in Figs. 1, 4 and 6, the body 70 1 is made in a shape it would assume if twisted about its longitudinal axis, that is to say: the top wall, as 4, of the horn at its outlet end is warped or twisted so it becomes a side wall, as 5, at the inlet end. The walls 75 of the sound-carrying channel of the horn thereby become warped planes.

In phonograph horns as adapted for use in present-day designs of cabinets, it is desirable that the flared outlet end 3 shall form 80 a part of the front of the cabinet and that the inlet 2 shall project upwardly through the motor board and that the tone arm of the instrument shall connect with the inlet 2 at the motor board. The inlet 2 may be 85 located centrally with respect to the side walls of the cabinet, or it may be located in one of the rear corners of the motor board. For purpose of illustrating my invention I have selected a horn adapted to the latter 90 arrangement.

The horn is capable of being easily and cheaply constructed of thin veneer or wood bent to proper form. In the preferred rectangular form shown in the drawings— 95 Fig. 3—both side walls 6 and 7 have the form of bent plane surfaces. In practice they are made of flat sheets of veneer bent to the desired form and constitute warped walls generated by vertical elements. Although the horn may have a neck that is bent both laterally and upwardly with a double curvature which produces in effect a twisted channel, yet the side walls are capable of being made of flat sheets of 100 veneer easily bent to the desired form, pro-

ducing a structure of great strength and rigidity.

Similarly the top and bottom walls may be bent to form without unduly straining 5 the wood.

While the above described mechanical arrangement of the walls forms an important part of my invention, a great acoustic advantage due to the twisted angular channel 10 construction above described, or its equivalent, is apparent from the remarkable tone results that are in practice secured from it.

Comparison through an exhaustive series 15 of tests of horns of various shapes has proven that not only is the resonance or increase in sound volume improved in this twisted form of horn, but also that the tone quality is greatly improved, there being a noticeable lack of sound wave interference 20 producing "beats," and a remarkable degree of blending or mellowness.

The mechanical causes for these effects I am not able at this time to fully explain, 25 although the results of the practical use of my invention conclusively prove that my improved angular twisted horn does produce the desirable results above enumerated.

The improved degree of resonance, or the increase in the volume of sound depending 30 upon synchronous vibration of the mass of partly inclosed air is possibly due to the fact that the comparatively flat but axially twisted walls present surfaces against which the incident sound waves impinge and are 35 reflected without the "damping" action that occurs when such sound waves strike and are deflected from a concave surface. The absence of interference or beats may be accounted for on the theory that a group of 40 sound waves projected down through the inlet 2 impinge upon and are reflected from the warped-plane walls and impinge successively against other warped-plane walls

a number of times before leaving the outlet.

3. The wall surfaces which are successively 45 impinged upon by a given sound wave are located angularly with respect to each other, and consequently two adjacent sound waves starting together at the inlet 2 would not be deflected alike from all of the successive 50 surfaces. Hence two sound waves of nearly the same pitch could not travel together a sufficient distance to produce interfering rarefactions and condensations. In other words, all the sound waves are so thoroughly 55 "mixed" in their passage through the horn by reason of the warped-plane angularly disposed walls that interference and beats due to overtones are almost, if not entirely, avoided.

60 The foregoing explanation of the possible mechanical reasons for the improved results which in practice I obtain by this device is merely offered as a possible explanation, but the spirit of my invention resides in the construction and arrangement of parts by which the foregoing results are attained rather than in the theoretical analysis of the mechanical reasons for their accomplishment.

65 Having thus described my invention, what I claim and desire to secure by Letters Patent is:

A horn for sound-reproducing instruments comprising a tapered body and an elongated neck, each of the side walls and top and bottom walls of said body and neck formed of a single piece of material bent to the 70 contour of said body, the neck portion of each of said walls twisted and turned upwardly, said walls forming a sound-carrying channel in which successive cross sections are in slightly rotated positions with relation to 75 each other.

80 In testimony whereof I affix my signature.

JOHN HERZOG.
